Austin H. Hart
BY
W. Jay Morrison
ATTORNEY

UNITED STATES PATENT OFFICE.

AUSTIN H. HART, OF MONTCLAIR, NEW JERSEY, ASSIGNOR, BY MESNE ASSIGNMENTS,
TO ROME RADIATION COMPANY, INC., A CORPORATION OF NEW YORK.

RADIATOR.

Application filed November 6, 1922. Serial No. 599,224.

To all whom it may concern:

Be it known that I, AUSTIN H. HART, a citizen of the United States, residing at Montclair, in the county of Essex and State of New Jersey, have invented new and useful Improvements in Radiators, of which the following is a specification.

This invention relates to radiators which may be built up by coupling together a plurality of sections or units, and has for an object to provide an improved radiator with component sections or units which can be coupled with either gaskets or screw nipples rapidly and inexpensively without stressing, twisting, distorting or injuring the thin metal shells of the units or sections; and which is simple, strong and durable. Other objects and advantages will be apparent from the following description of an embodiment of the invention, and I will hereinafter particularly point out the novel features in claims.

In the accompanying drawing:

Fig. 1 is a front elevation of one of the units or sections constructed in accordance with the invention.

Fig. 2 is a transverse section of the same taken substantially along the line 2—2 of Fig. 1.

Fig. 3 is a fragmentary transverse section of the same taken substantially along the line 3—3 of Fig. 1, and

Fig. 4 is a perspective of the bushing.

In the illustrated embodiment of the invention, each unit or section comprises a tubular metal shell 1 which is formed around and upon a metal bushing 2. The bushing is provided with lateral flanges 3 having there-in apertures 4 that are parallel to the main passage of the bushing. The shell is secured to the flanges around the apertures 4 so that these apertures will not be in communication with the interior of the shell. The shell is preferably formed upon the bushing by electro-deposition of metal such as copper. For example, the bushing may be set into a frame of lead or other metal or alloy fusing at a low temperature, which frame has a shape and size corresponding to the desired interior of the shell. This frame is then plated with copper by the use of a current of electricity and a suitable electrolyte in which the metal frame and bushing are immersed. After the coating of copper has reached the desired thickness, the coated

frame is removed and heated to fuse out the metal frame and leave the copper shell securely attached to the bushing.

The inner peripheral surface of the bushing is oppositely threaded from each end, 60 and between the ends is provided with one or more passages 5 which connect the passage of the bushing with the interior of the shell.

When a plurality of the sections are 65 brought together face to face with the bushings aligned, suitable gaskets 6 (Fig. 2) may be interposed between the abutting end faces of the bushings to connect their passages and seal the connection between 70 them. Coupling bolts or rods 7 may be passed through the aligned apertures 4 of the flanges and with suitable nuts serve to clamp the sections together. Since the coupling stresses are taken up entirely by the 75 bushings, there will be no twisting or distortion of the shell.

Screw nipples 8 may be used to connect the adjacent sections, as illustrated in Fig. 3, 80 by threading the same into the adjacent ends of two abutting bushings. Since the threads at the opposite ends of each bushing are opposite in direction, rotation of an interposed threaded nipple in one direction will couple two adjacent bushings together and 85 rotation in the opposite direction will uncouple them. To prevent distortion or twisting of the shell while the nipples are being screwed into the bushings, the bushings may be held against rotation in any 90 suitable manner such as by inserted tools (not shown) with lugs thereon that fit into the passages 5 and interlock therewith. When the coupling has been completed the tools may then be withdrawn. The bolts 7 95 may also be passed through the aligned apertures 4 of the bushings to prevent twisting or distortion of the shell while the nipples are being threaded into the bushings. The bolts then subsequently assist in 100 coupling the sections so as to prevent rotation of any section upon a nipple or relatively to the other sections.

With this construction of radiator sections and assembled radiator, a comparatively 105 thin shell may be employed, and the bushings will take up all twisting or distorting stresses and prevent their transmission to the shell. The conduits of the bushings may be connected by either the nipples or gaskets, 110

and communication between the connected bushings and the interiors of the shells is effected through the passages 5.

It will be understood that various changes may be made by those skilled in the art in the details and arrangements of parts of the embodiment described herein and illustrated for the purpose of explaining the nature of the invention, within the scope of the appended claims.

I claim:

1. A radiator section comprising a shell, a coupling bushing to which the shell is secured, said bushing having apertured lateral extensions to which the shell is firmly secured around the apertures so as to form apertures through the sections offset from the bushing aperture and closed from the interior chamber of the shell, whereby the sections can be secured firmly together at the bushings either temporarily or permanently.

2. A radiator section comprising a bushing having a threaded aperture and apertured lateral extensions, and a tubular shell formed upon the bushing including the extensions and around the apertures, whereby when the sections are to be connected through coupling conduits threaded into adjacent ends of the threaded apertures of the

bushings, rods may be passed through the 30 apertures of the extensions to prevent twisting and distortion of the shell.

3. A radiator section comprising a bushing 35 with its inner peripheral surface oppositely threaded from each end and having an apertured laterally disposed flange, a tubular shell in which the bushing is secured with the flange aperture forming a passage through the shell from face to face, through which may be passed a bolt for coupling together a plurality of sections abutting face to face, the bushing having therein a passage connecting its inner peripheral surface with the interior of the tubular shell.

4. A radiator section comprising a bushing 40 having a main passage and one or more auxiliary passages disposed parallel to and laterally of the main passage, a tubular shell of metal electro-deposited around and upon the bushing, whereby the main passage 45 serves as a connecting conduit between coupled sections and the auxiliary passages permit the passage of coupling rods through abutting sections.

In testimony whereof I have hereunto set 55 my hand.

AUSTIN H. HART.
